HEAT DISSIPATOR

Robert L. Branson, 1224 E. Christy Drive,
Phoenix, Ariz. 85020

Filed Nov. 20, 1974, Ser. No. 525,352

Term of patent 14 years

Int. Cl. D13—99
U.S. Cl. D26—1 R

FIG. 1

FIG. 2

FIG. 3

FIG. 4

FIG. 1 is a top perspective view of a heat dissipator showing my new design;

FIG. 2 is a bottom perspective view thereof;

FIG. 3 is a top plan view thereof; and

FIG. 4 is a cross sectional view taken on line 4—4 of FIG. 3.

I claim:

The ornamental design for a heat dissipator, as shown.
